UNITED STATES PATENT OFFICE.

HENRY W. FESSER, OF SACRAMENTO, CALIFORNIA.

CARD HOLDER.

1,415,540.

Specification of Letters Patent. Patented May 9, 1922.

Application filed May 25, 1921. Serial No. 472,410.

To all whom it may concern:

Be it known that I, HENRY W. FESSER, a citizen of the United States, residing at Sacramento, in the county of Sacramento and State of California, have invented new and useful Improvements in Card Holders, of which the following is a specification.

This invention relates to a card holder, and particularly pertains to means for supporting show cards and the like.

It is a principal object of the present invention to provide a support for show cards which will be sightly in its appearance; and is further formed to adjustably support a card and to permit the card to be readily disposed in a supported position thereon.

The present invention contemplates the use of a pedestal adjustably supporting a stem at the upper end of which a yieldable fastening for a card is provided, means also being supplied for holding the card in an aligned position.

The invention is illustrated by way of example in the accompanying drawings, in which Fig. 1 is a view in elevation showing the complete device, with parts broken away, and indicating a card by dotted lines.

Fig. 2 is a view in elevation showing the stem to which the card is attached.

Referring more particularly to the drawing, 10 indicates a base member, here shown as being circular in formation and as carrying a vertically disposed tube 11. This tube is fitted at its upper end with a collar 12, having a laterally extending threaded opening therethrough. A set screw 13 passes through this opening and may be forced against a stem 14. The stem 14 telescopes within the tube 11, and thus may be adjustably held relative thereto by the set screw.

Mounted upon the upper end of the stem is a fastener 15. This element consists of a helical coil of spring wire, threaded through an eye 16 in the stem and being arranged upon opposite sides thereof. It is convenient to dispose two or more convolutions of the coil on each side of the stem, thus providing clamping jaws between which a card 17 may be yieldably held. Fixed to the top of the stem is a horizontally extending plate 18 which is held by a screw 19. The top of a card is adapted to reverse with the under face of this plate and thus be held in an aligned position.

In operation of the present invention the stem 14 may be adjustably disposed relative

to the base structure, after which the set screw 13 is tightened. A display card 17 may then be mounted upon the device by springing adjacent convolutions of the support 15, in order to insert the upper edge of the card therebetween, after which the card will be firmly held thereby. If it is desired to display more than one card, a second card 17^a may be inserted between the convolutions of the helical spring, as shown in the drawings. This card will extend upwardly and in no way interfere with the card disposed below it.

It will thus be seen that the device here disclosed, while simple in its construction, provides effective means for supporting a card and permitting it to be readily interchanged.

While I have shown the preferred form of my invention as now known to me, it will be understood that various changes in the combination, construction and arrangement of parts may be made by those skilled in the art, without departing from the spirit of the invention as claimed.

Having thus described my invention, what I claim and desire to secure by Letters Patent is:

1. A device of the character described comprising a vertically disposed standard having a supporting base, a helical spring, secured at its center to the standard and having a plurality of its convolutions disposed on opposite sides of the standard for supporting one or more cards or like articles to be displayed.

2. A device of the character described a vertically disposed standard, a helical spring secured thereto adjacent one end thereof and having a plurality of convolutions disposed on opposite sides of said standard for gripping cards or like articles to be displayed.

3. A device of the character described, comprising a base, a supporting member carried thereby, a coiled spring clip mounted at the outer end of said member and between the convolutions of which a card may be gripped, and a plate at the end of said support by which the card may be held with its top edge disposed in a horizontal position.

4. In a device of the character described, the combination, with a vertically adjustable standard having a transverse opening adjacent one end thereof, of a helical spring threaded through the said opening to dispose a plurality of convolutions thereof

upon opposite sides of the standard for supporting a card or like article interposed between the convolutions.

5. In a device of the character described, the combination, with a vertically adjustable standard having a transverse opening adjacent one end thereof, of a helical spring threaded through the said opening to dis-

pose a plurality of convolutions thereof upon opposite sides of the standard for supporting a card or like article interposed between the convolutions, and a plate at the upper end of said standard by which a card may be held in position. 10

HENRY W. FESSER.
